PHOTOCOPYING APPARATUS

Donald A. Buckingham, Kenilworth, Ill.
(1414 Roscoe, Chicago 13, Ill.)

Filed July 6, 1962, Ser. No. 70,826

Term of patent 14 years

(Cl. D61—1)

The figure on the drawing is a front perspective view of a photocopying apparatus showing my new design.

The left side of the machine, not shown, is substantially similar to the side shown; while the rear of the machine and the top of the upper raised door, not shown, are plain and unornamented.

The essential features of the design reside in the portions shown in solid lines.

I claim:

The ornamental design for a photocopying apparatus, substantially as shown and described.
